UNITED STATES PATENT OFFICE.

HARRY FEALIX JOSEPH CLARKE, OF MAQUOKETA, IOWA.

SWIMMING GLOVE.

1,413,967.

Specification of Letters Patent. Patented Apr. 25, 1922.

Application filed March 10, 1921. Serial No. 451,408.

To all whom it may concern:

Be it known that I, HARRY FEALIX JOSEPH CLARKE, a subject of the king of England, residing at Maquoketa, in the county of Jackson and State of Iowa, have invented a new and useful Swimming Glove, of which the following is a specification.

The device forming the subject matter of this application is a glove, and one object 10 of the invention is so to construct the glove that it will facilitate the operation of swimming, and enhance the hold of the swimmer on the water.

Another object of the invention is to provide 15 novel means for connecting the glove to the hand.

It is within the province of the disclosure to improve generally and to enhance the utility of devices of that type to which the 20 invention appertains.

With the above and other objects in view, which will appear as the description proceeds, the invention resides in the combination and arrangement of parts and in the 25 details of construction hereinafter described and claimed, it being understood that, within the scope of what is claimed, changes in the precise embodiment of the invention shown can be made without departing from 30 the spirit of the invention.

In the accompanying drawings:—

Figure 1 shows in top plan, a glove constructed in accordance with the invention; Figure 2 is a longitudinal section of the 35 glove; Figure 3 is a cross section on the line 3—3 of Figure 1; and Figure 4 is a cross section on the line 4—4 of Figure 1.

The glove forming the subject matter of this application preferably is made out of 40 rubber, although any other material may be used. The glove comprises a body 1 which is concaved as shown at 2. Around the major portion of its periphery, the body

1 is folded to form a marginal flange 3. One end of the body 1 overlies the body and is 45 secured thereto as indicated at 4, the said end of the body defining a loop 5. The transverse edge of the part which forms the loop 5 abuts against the ends 6 of the flange 3. Retainers 7, in the form of strips are 50 provided, the ends of the retainers 7 being engaged and secured between the flange 3 and the body 1, as indicated at 8. Between the retainers 7, the flange 3 is secured to the body 1. The numeral 9 denotes a retainer 55 which may be in the form of a strap, the retainer 9 being received and held in the loop 5. The ends of the retainer 9 may be connected by a buckle 10, or in any other suitable way.

In operation, the fingers of the wearer are inserted beneath the retainers 7, the retainer 9 being buckled around the wrist. Owing to the concavity 2 which exists in the body 1, the article will give the hand of a swimmer 65 an increased hold on the water and render it possible for the wearer to swim with greater ease and speed than would be the case if the glove were not worn.

Having thus described the invention, what 70 is claimed is:—

A swimming glove comprising a concaved body folded at its edge to form a marginal flange, one end of the body overlying the body and being secured thereto to form a 75 loop; a first retainer having its ends engaged between the flange and the body; and a second retainer received in the loop.

In testimony that I claim the foregoing as my own, I have hereto affixed my signature in the presence of two witnesses.

HARRY FEALIX JOSEPH CLARKE.
